AIR OR GAS COMPRESSOR

Application filed June 13, 1930. Serial No. 460,812.

This invention relates to an air or gas compressor and more particularly to a simple, inexpensive and efficient system and mechanism for maintaining a predetermined pressure in the crankcases of compressors of the enclosed crankcase type.

In compressors of the enclosed crankcase type, especially those wherein the crankcase is connected to the compressor suction port to prevent leakage to the atmosphere of the fluid compressed, the lubricating oil pump being positioned in the crankcase is subjected to the pressure therein and consequently may be submerged in a vacuum which effects its performance, causing spasmodic or interrupted oil delivery and consequently inefficient lubrication of the wear surfaces of the compressor with the resulting inefficiency of operation and decrease in the life of the compressor.

Also in compressors of this type, the pressure in the crankcase when below atmosphere, may permit the inrush of atmospheric air through the shaft packing or crankcase entrance thereby reducing the efficiency of the system.

It is an object of the present invention to provide a line of communication between the crankcase and suction port or chamber of enclosed crankcase compressor in which line of communication is located a pressure operated relief valve, tensioned to maintain a predetermined pressure in the crankcase of the compressor to overcome the undesirable features above pointed out and insure efficient operation of the lubricating oil pump as well as prevent the inrush of atmospheric air into the crankcase and also to provide means whereby said automatic pressure operated relief valve may be rendered inactive for the purpose specified at certain times or under certain conditions.

With these and other objects in view, as may appear from the accompanying specification, the invention consists of various features of construction and combination of parts, which will be first described in connection with the accompanying drawing, showing a compressor of the preferred form embodying the invention, and the features

forming the invention will be specifically pointed out in the claims.

In the drawing

Fig. 1 is a vertical section through a compressor embodying the present invention. 55

Fig. 2 is an enlarged fragmentary section of the automatic or pressure operated relief valve.

Referring more particularly to the drawing, a vertical air or gas compressor of the crankcase type is shown in the drawing but it is to be understood that the present invention may be used in connection with any approved type of enclosed crank compressor without departing from the spirit of this invention. 65

The compressor 1 comprises the usual cylinder 2 in which the piston 3 reciprocates for compressing the fluid, which is drawn into the cylinder through the suction valve structure 4, suction chamber 5 and suction or inlet port 6, while it is discharged from the cylinder through the discharge valve 7 and discharge port or passage 8. 70

The crankcase 9 of the compressor is enclosed so as to prevent leakage to atmosphere of any fluid or gas which might leak past the piston 3 into the crankcase and to prevent the building up of excessive pressure in the crankcase as well as to provide an outlet for the fluid or gas, which leaks into the crankcase, a line of communication is provided between the crankcase 9 and the suction chamber 5 of the compressor. In the drawing, this line of communication is shown as composed of a line of piping including the pipes 10, 11, 12 and 13, which are positioned exteriorly of the compressor although it is to be understood that this line of communication may be within the compressor casting itself or at any other suitable location without departing from the spirit of this invention. 85

To prevent the compressor suction from lowering the pressure in the crankcase to the degree of pressure whereby it will interfere with the operation of the lubricating pump (not shown), a pressure relief valve structure 14 is connected in the line of communication between the crankcase 9 and the suction chamber 5. 90

The pressure relief valve structure 14 includes a valve seat 15 in the line of communication against which the valve 16 is urged and held seated by the spring 17. The spring 5 17 engages the disc 18 which is positioned against one side of the diaphragm 19, while the valve 16 engages the opposite side of the diaphragm and is held tightly in engagement therewith by means of the spring 20. The 10 diaphragm 19 forms one wall of the chamber 21 within the relief valve structure 14 and this chamber 21 opens into the crankcase 9. When the pressure within the crankcase 9 and consequently in the chamber 21 builds up suff- 15 ficiently, it will flex the diaphragm 19 against the tension of the spring 17 and move the valve 16 off its seat 15 thereby opening the crankcase 9 to the suction chamber 5, which will permit the compressor to suck or draw 20 the gas, air or the like from the crankcase 9 for recompression. When the pressure in the crankcase 9 falls sufficiently or less than the tension of the spring 17, the spring will act to seat the valve 16 and cut off the communication between the suction of the compressor in the crankcase 9 until such time as the pressure in the crankcase again exceeds 25 the tension of the spring 17.

The tension of the spring 17 may be regu- 30 lated as desired to vary the pressure requirements for unseating the valve 16 by means of the tension regulator structure 22, which is of the usual adjustable bolt and disc type as shown in Fig. 1.

35 At times it is desirable to open the crankcase 9 to the suction of the compressor irrespective of the pressure in the crankcase and consequently render the relief valve 14 inactive for the purpose for which it is devised and to permit such operation, a bypass arrangement is provided.

40 In Fig. 1 of the drawing, this bypass arrangement comprises a pipe 23, which opens into the chamber 21 and into a valve 24, which is connected by means of a pipe 25 with the pipe 12 and when the valve cone 26 of the valve 24 is unseated, a bypass arrangement around the valve 16 is provided; however, when the valve cone 26 is seated, such bypass 45 is cut off. The valve structure 24 may be of any approved type of valve preferably a manually operated valve in which the cone 26 is seated or unseated by rotation of the stem 27.

50 It will be understood that the invention is not to be limited to the specific construction or arrangement of parts shown but that they may be widely modified within the invention defined by the claims.

55 What is claimed is:—

1. The combination with an air or gas compressor of the enclosed crankcase type having suction and discharge ports and having a passage establishing communication between the crankcase and suction port of the

compressor, said discharge port being free from connection with said crankcase of a pressure actuated valve acted upon by the pressure within the crankcase for opening and closing said passage, and adjustable 70 means cooperating with said valve to tension the valve to permit regulation of the pressure at which the valve opens or closes, a bypass about said pressure actuated valve to permit communication between the compressor suction port and the crankcase irrespec- 75 tive of the pressure actuated valve, and a valve in said bypass.

2. In an air or gas compressor embodying suction and discharge ports and an enclosed 80 crankcase, said discharge port being free from connection with said crankcase whereby the fluid compressed by the compressor will not enter the crankcase, and pressure actuated means operable upon creation of a 85 predetermined pressure in the crankcase to open communication between the crankcase and suction port for lowering the pressure in the crankcase.

3. In an air or gas compressor embodying 90 suction and discharge ports and an enclosed crankcase, said discharge port being free from connection with said crankcase whereby the fluid compressed by the compressor will not enter the crankcase, a pressure actuated 95 valve operable upon creation of a predetermined pressure in the crankcase to open communication between the crankcase and suction port for lowering the pressure in the crankcase, and adjustable means for regulating the tension of said valve for regulating the pressure at which the valve opens or closes.

4. In an air or gas compressor embodying 100 suction and discharge ports and an enclosed crankcase, said discharge port being free from connection with said crankcase whereby the fluid compressed by the compressor will not enter the crankcase, a pressure actuated 105 valve operable upon creation of a predetermined pressure in the crankcase to open communication between the crankcase and suction port for lowering the pressure in the crankcase, adjustable means for regulating the tension of said valve for regulating the 110 pressure at which the valve opens or closes, and manually controlled means for opening the suction chamber to the crankcase irrespective of said pressure actuated means.

115 In testimony whereof I affix my signature.

120 SYLVAN R. HIRSCH.
